UNITED STATES PATENT OFFICE.

BENJAMIN E. LAWRENCE, OF CHICAGO, ILLINOIS, ASSIGNOR TO B. E. LAWRENCE & CO., INC., A CORPORATION OF ILLINOIS.

MENU-CARD HOLDER.

Application filed June 20, 1923. Serial No. 646,521.

To all whom it may concern:

Be it known that I, BENJAMIN E. LAWRENCE, a citizen of the United States of America, and a resident of Chicago, county 5 of Cook, and State of Illinois, have invented a new and useful Improvement in Menu-Card Holders, of which the following is a specification.

This invention relates to holders, and 10 particularly loose leaf holders.

The main objects of this invention are to provide improved means for attaching a hook to a supporting member without the use of soldering or other similar fastening 15 means; to provide improved means of the above kind adapted for use with loose leaf binders, and particularly for menu card holders of the type wherein a pair of hooks are arranged on a back between hinged 20 covers for the attachment of the sheet; to provide an improved construction and arrangement of resilient means for normally closing the covers of a loose leaf holder and which will permit the covers to be 25 folded back upon themselves without injury to the hinge connection; and to provide an improved mounting for the back of a loose leaf holder which will permit it to be partially rotated independently of the covers 30 when the covers are open.

An illustrative embodiment of this invention is shown in the accompanying drawings, wherein:

Figure 1 is a plan of a menu card holder 35 to which this invention is applied, showing the cover members in open positions, part of the inner frame sections being broken away to show the spring mounting.

Fig. 2 is a longitudinal section of the back 40 showing the telescoping members in their extended positions for the insertion of the hooks.

Fig. 3 is a central section of the holder, the view being taken through the back and 45 showing a loose sheet being inserted into the holder.

Fig. 4 is a side elevation of the back having attached thereto a sheet which is shown partly in section.

Fig. 5 is an enlarged fragmentary top 50 plan of the holder, showing a sheet held between the cover members which are partly open, one of the pivot pins of the back being shown in section.

Fig. 6 is an enlarged fragmentary detail 55

of the holder, showing part of the mounting in dotted outline.

In the form shown, the holder includes a back of improved construction on which is mounted an improved arrangement of hooks 60 for engagement with apertures in the crease of a folded menu card to be inserted between a pair of hinged cover members which are connected to each other and to the back by an improved mounting.

Referring to the drawings, the holder comprises a back 1, on which is mounted a pair of hooks 2 for engagement with apertures 3 formed in the crease of a folded menu card 4, or other sheet to be inserted 70 in the holder between hinged cover members 5. The cover members 5 are hinged together by an improved form of mounting 6, which includes means for pivotally supporting the back 1.

In the form shown, the back 1 includes a pair of tubular telescoping members 7 and 8, having openings 9 and 10 respectively formed therein adjacent each end of the back for receiving the hooks 2. As illustrated, 80 the openings 9 of the outer member 7 are arranged to fully register with the opening 10 of the inner member 8 only when the two telescoping members are relatively shifted to the extended positions shown in Fig. 2. 85 The openings 9 and 10 are of sufficient size to permit the shanks of the hooks 2 to be readily inserted into the inner member 8 when the openings are in full register.

In the particular construction shown, the 90 fastening hooks 2 are formed of a heavy gage of wire which is bent to form a substantially straight shank 11 and a retaining part 12, the end of which is slightly curved to facilitate the insertion of the leaf. The 95 retaining part 12 is arranged so as to be spaced slightly from the tubular member 7, when the shank 11 is held within the inner member 8. In the event that a filler tube is used, it would be provided with openings 100 corresponding with the openings 10 of the tube 8. The hooks 2 are arranged on the back 1 with their inner ends pointed toward each other, so as to permit the sheet 4 to be inserted only when buckled transversely 105 of itself, as shown in Fig. 3, and then flattened. To facilitate the insertion of the leaf, the base parts 13 of the hooks 2 are disposed substantially perpendicularly to the back 1. The improved arrangement of the 110

hooks 2, herein shown, prevents removal of the sheet from the holder without first buckling the sheet as in its insertion. The telescoping members 7 and 8 are relatively shifted to the positions shown in Fig. 3, wherein they coact to reduce the effective sizes of the openings 9 and 10, thereby locking the hooks against removal. Suitable means, such as rivets 14, secure the telescoping members 7 and 8 against relative shifting after the hooks are mounted on the back. The improved construction of back 1, herein shown, permits the holder to be readily assembled and does away with the use of 15 solder or similar fastening means.

The cover members 5 are preferably formed to provide frames for supporting advertising cards, or menu cards containing lists of special items in addition to those 20 which appear on the folded sheet.

As illustrated, each of the cover members 5 comprises channel-shaped sections 15 and 16, which are secured together by rivets 17, so as to form a frame for a pair of celluloid 25 or other transparent sheets 18, for enclosing the advertising card or the special menu sheet, not shown. The edges of the transparent sheets 18 are fitted in the channel sections 15 and 16 and are secured against 30 displacement by rivets 19 extending through the sections 15. The cover members 5 are similar in construction to those shown in my Patent No. 1,444,193, issued February 6, 1923.

35 The mounting 6 includes a pair of oppositely disposed substantially U-shaped springs 20, having arms 21 connecting the cover members 5 together at the upper and lower ends of the frame sections 15. The 40 spring arms 20 extend inwardly into the channel sections 15 and their inner ends are secured against turning relative to the cover members by being bent transversely across the channel sections, as shown at 22. The 45 springs 20 are arranged so as to permit the covers 5 to remain slightly open when the holder is standing upright, as in use on a table. In any other position of the cover members 5, the spring arms 21 are placed 50 under torsional strain. When the holder is lying down flat on one of the covers 5, the other cover closes by its own weight after being substantially closed by the action of the springs 20. With this improved arrangement of spring mounting the cover members may be folded back upon themselves without injury to the spring. The spring prevents the covers from being left 55 open when the holder is lying on a table.

60 Mounted on the base parts 23 of the springs 20, are bearing members 24, formed to receive pivot pins or studs 25, which extend into the ends of the tubular back 1. In the form shown, the studs 25 are riveted 65 to the back 1 by the rivets 14. The studs 25

have heads or knobs 26 which project slightly beyond the upper and lower edges of the cover members 5, so as to prevent the sharp corners of the channel sections 15 and 16 from coming in contact with and marring the surface of the table or other support on which the holder may be placed. The improved pivotal mounting of the back 1 permits the back to be partially rotated independently of the springs 20 and of the covers 75 5, so that the menu sheet may be readily turned in the holder while the covers are fully open.

The operation of inserting a loose leaf into the holder is believed to be clear from the 80 foregoing description.

Although but one specific embodiment of this invention has been herein shown and described, it will be understood that numerous details of the construction shown may be altered or omitted without departing from the spirit of this invention as defined by the 85 following claims.

I claim:

1. A loose leaf holder comprising a back 90 having a pair of cover members hinged thereto, and a pair of hooks on said back for engagement with apertures in a leaf to be inserted in the holder, both of said hooks being disposed in a single plane, said hooks being spaced apart longitudinally of said back and having their free ends pointed inward toward each other to permit the leaf to be inserted only when buckled transversely of itself at its medial part and then 100 flattened so as to be held between said hooks and back.

2. A loose leaf holder comprising a back having a pair of cover members hinged thereto, and a pair of hooks on said back for engagement with apertures in a leaf to be inserted in the holder, both of said hooks being disposed in a single plane, said hooks being spaced apart longitudinally of said back with their base parts disposed substantially perpendicular to said back and having their free ends pointed inwardly toward each other to permit the leaf to be inserted only when buckled transversely of itself at its medial part and then flattened so as to be held between said hooks and back. 110

3. A holder comprising a pair of telescoping members, and a hook having a shank extended through an opening in one of said members, said telescoping members being relatively shifted so as to reduce the effective size of said opening for locking said hook in the holder. 115

4. A holder comprising a pair of telescoping members, a hook having a shank extended through an opening in one of said members, said telescoping members being relatively shifted so as to reduce the effective size of said opening for locking said hook in the holder, and means for securing said 125 130

telescoping members against relative shifting in their hook locking positions.

5. A holder comprising a pair of telescoping members having registering openings, and a hook having a shank extended through said openings, said telescoping members being relatively shifted so as to reduce the effective sizes of said openings for locking said hook in the holder.

10 6. A holder comprising a pair of telescoping tubular members having registering openings, and a hook having a shank inserted through said openings and extending axially within the inner one of said members, said members being relatively shifted axially so as to reduce the effective sizes of said openings for locking said hook in the holder, said telescoping members being riveted together to secure them against relative shifting in their hook locking positions.

7. A loose leaf holder comprising a back having a pair of cover members hinged thereto, said back including telescoping parts, and a pair of hooks for insertion 25 into apertures in a sheet to be held in the holder, said hooks having shanks extended through openings in one of said telescoping parts, said telescoping parts being relatively shifted so as to reduce the effective sizes of 30 said openings for locking said hooks to the back.

8. A loose leaf holder comprising a pair of cover members, a resilient element connecting said covers, and a back pivotally 35 connected to said resilient element and having means for the attachment of a sheet.

9. A loose leaf holder comprising a pair of cover members, a substantially U-shaped spring having its arms fixed on said cover 40 members and arranged to be placed under torsional strain when said covers are open, and a back pivotally connected to said spring and having means for the attachment of a sheet.

45 10. A loose leaf holder comprising a pair of covers, channel members extending along the inner edges of said covers, a substan-

tially U-shaped spring having its arms located in said channels, the ends of said arms being bent transversely to said arms in the 50 plane of the respective cover and coacting with said channels to place said arms under torsional strain when said covers are open, and a back pivotally connected to said spring and having means for the attachment of a 55 sheet.

11. A loose leaf holder comprising a pair of covers, channel members extending along the inner edges of said covers, a substantially U-shaped spring having its arms located in said channels, the ends of said arms being bent transversely to said arms in the 60 plane of the respective cover and coacting with said channels to place said arms under torsional strain when said covers are open, and a back pivotally connected to said 65 spring.

12. A loose leaf holder comprising a pair of hinged covers having their inner opposed edges spaced apart, a pair of substantially U-shaped springs arranged at respectively opposite ends of said covers and having their arms secured to said inner edges, bearing 70 members on the base parts of said U-shaped springs, pivot pins on said bearing members, and a back arranged between said covers and secured to said pins.

13. A loose leaf holder comprising a pair of hinged covers having their inner opposed edges spaced apart, a pair of substantially U-shaped springs arranged at respectively opposite ends of said covers and having their arms secured to said inner edges, bearing 80 members on the base parts of said U-shaped springs, coaxial pivot pins extending through said bearing members, a back arranged between said covers and secured to the inner ends of said pins, and knobs on the outer ends of said pins projecting beyond the ends of said covers.

90 Signed at Chicago this 18 day of June 1923.

BENJAMIN E. LAWRENCE.
